Patented Oct. 12, 1920.

UNITED STATES PATENT OFFICE.

LESLIE SALTER, OF VALLEJO, CALIFORNIA.

ARMOR-PLATE INSTALLER.

1,355,784.

Specification of Letters Patent.

Patented Oct. 12, 1920.

Application filed February 21, 1920. Serial No. 360,494.

To all whom it may concern:

Be it known that I, LESLIE SALTER, a citizen of the United States, residing at Vallejo, in the county of Solano and State of California, have invented a new and useful 5 Armor-Plate Installer, of which the following is a specification.

The present invention relates to a device for placing armor plates on battleships and 10 the objects of my invention are as follows:

One of the most difficult problems in modern ship construction is the installing of armor plates around the hull of the ship. These plates, which weigh as high as 75 tons, 15 are, in present day practice, lifted by heavy cranes to a height corresponding to the height of the place on the hull of the ship which they are intended to fill. Usually it is impossible for the crane to bring such a 20 plate into close proximity with its permanent place because in some cases the top of the hull of the ship protrudes beyond the place where the plate is to be installed and in other cases the plate itself is curved 25 downwardly and inwardly so that even if the top of the plate can be brought into close proximity, the bottom of the plate will depend in a position several feet away from the hull of the ship. While the plate is thus 30 suspended from the crane as near its permanent place as the crane can get it, it has been the usual practice to pull it toward the ship by means of heavy wire cables attached to the plate in different convenient places, and 35 acted upon by a crew of men working on the inside of the ship. Since this operation is performed after the ship is launched, that is, after the frame and hull of the ship are completed, it is extremely difficult for the 40 inside crew to work with any degree of efficiency, all the more since by the double bottom tank, which usually follows the lines of the hull to a height corresponding to the height of the armor plate, the part 45 of the ship next to the hull is divided into a large number of small compartments, accessible through small manholes only. To exert any power on the cables fastened to the armor plate, calls for a large number 50 of men and for a high degree of ingenuity on the part of the crew in gaining a solid foothold for themselves and in placing their block and tackle. Under these circumstances it is necessary on a modern battleship to employ a crew of about twelve men 55 on the inside of the ship and the installing

of two plates is considered a good day's work.

Installing an armor plate this way is furthermore accompanied by grave danger 60 for the crew, since not infrequently a defective wire cable will give way to the heavy weight of the plate and break.

My device overcomes most of these difficulties by permitting practically all of the 65 work to be done from the outside of the ship, where a floating deck gives convenient foothold to the crew. It further replaces the pulling operation by a sliding operation, by which the heavy plate slides comfortably 70 into its place on two rails previously attached to the hull of the ship in a slanting direction.

While my device is primarily intended for the installing of armor plates on battleships, it may, with slight modifications, be used to advantage in the installing of ordinary plates on any steel ship and such a use would not depart from the spirit of this 75 invention.

I attain these objects by the mechanism 80 illustrated in the accompanying drawing, in which—

Figure 1 represents an outside elevation of my device in its position on the outside 85 of the hull of the ship, looking toward the ship.

Fig. 2 represents an outside elevation of 90 my device in its position on the outside of the hull of the ship, looking aft.

Fig. 3 represents a detail, showing the manner in which the lower extremities of 95 my device are fastened to the hull of the ship.

Similar numerals refer to similar parts 95 throughout the several views.

The shell 1, the tank top 2, the floor plates 3, the longitudinal plates 4 and the angles 5 binding these different plates constitute the frame and hull as far as is necessary to 100 show for the purposes of this illustration. The armor shelf 6, consisting of a strong angle, is riveted to the hull of the ship, as shown at 10, the full length of the same, so that its free flange provides a resting place 105 for the armor plate 7 to be installed. My device consists chiefly of two strong beams 8, preferably of wood, the bottoms 9 of which are fastened to the armor shelf 6, at a distance from each other less than the 110 width of the armor plate 7. These two beams slant upward, away from the hull of

the ship so as to leave sufficient space between their tops 11 and the hull of the ship to allow the armor plate 7 to pass between them. The two beams also slant, in their 5 relation to each other, in an outward direction, so that the distance between their tops 11 is larger than the width of the armor plate 7. The tops 11 are held in their spaced relation by a strong rod 12, consisting of 10 two parts 13 and 14, joined by a turn buckle 15, which allows of some adjustment in the length of the rod. The outer ends of the two parts 13 and 14 are fastened to the tops of the beams 8 in any convenient way, preferably, as here shown, by eyes 20 fitting into 15 shackles 16 bolted to steel extensions 30 of the tops 11 of beams 8.

The bottoms of the two beams 8 are fastened to the armor shelf angle 6 as follows: Angle clips 17, of convenient size, but of considerably smaller dimensions than the armor shelf angle 6, are tapped on to the under side of the horizontal flange of the latter, so that both flanges of the angle 20 25 run parallel to the flanges of the armor shelf angle but sufficient space is left between the two flanges toeing downward to allow a nut 18 to be screwed to the threaded end of a rod 19 going through a hole 21 in the perpendicular flange of angle clip 17. The lower end of beam 8 is provided with 30 35 hole 23 to receive the other threaded end of rod 19, a washer 24 and a nut 25 preventing the beam from sliding off. Since the armor plate is usually a few inches thicker than the width of the armor shelf angle, sufficient space is left between the toe of the horizontal flange of the armor shelf angle and the beam, to allow the armor 40 plate to slide down to the armor shelf angle between the beams and the hull of the ship.

To relieve the shearing stress which must necessarily be experienced by the angle clip 17 on account of the heavy weight of the 45 beams as well as of the armor plate, another means of resisting the downward pressure of the beams and armor plate is provided by a strong wire cable 26 attached in some convenient manner to a flanged plate 50 55 27 fastened to the bottom of beam 8 and led upward to a clamp 28, which clamps over the top of the hull, secured by a set screw 32. A turnbuckle 29, introduced at some convenient place in the length of the cable 26, permits the adjustment of the length of the latter.

The shackles 16 fitted on to the extensions 30 of beams 8 serve also to engage one end of strong wire cables 33, the other ends of 60 which are attached to clamps 34, adapted to be clamped over the top of the hull of the ship and to be secured there by set screws 40.

While the two beams are here shown as slanting away from each other in an upward direction, this is not necessary for the pur-

poses of this invention. The same result might be accomplished by arranging them in a parallel position, their distance from each other being less than the width of the armor plate, provided the two cables 33 are 70 kept far enough apart to allow the armor plate to pass between them.

The two edges of each of the beams 8 nearest to the hull of the ship are provided with angles 35, which serve as rails for the 75 armor plates to slide on.

The device is operated as follows:

The whole device, consisting of two beams 8, the connecting rod 12, and the respective cables and accessories, is lifted by either one 80 of the shackles 16 by means of a crane into a position that it clears the top of the hull, hanging somewhat outside the body of the ship. It is then lowered gradually so that the four clamps 28 and 34 successively reach 85 the top of the hull, where they are clamped over the latter and fastened to it by set screws 32 and 40. A further lowering of the device will bring the beams, by mere force of gravity, very nearly in their desired 90 position. The lower ends of the two beams are then fastened to the angle clips 17 by means of rods 19, and the hold of the crane may be released, the device now being in its proper place. The armor plate is brought 95 up by the crane and lifted into a position where it hangs perpendicularly over the two beams 8. It will then be lowered gradually until its lower edge touches the two beams, after which it will slide down the edges of 100 the beams into its proper place, where it may easily be fastened in the usual manner. Should the fit of the plate between the hull of the ship and the beams be either too tight or not tight enough, it may be easily adjusted by a few turns of the screw 25 on rod 19. After the top of the plate has been secured to the hull of the ship by a few bolts, the plate is held firmly in its position between the beams and the hull, and the 110 hold of the crane may be released, thus reducing the time during which the crane is in actual use in installing the plate from several hours to 10-15 minutes.

The device is moved by simply unscrewing 11 nut 18 from rod 19, after which it may be lifted to the next position, ready to take the adjoining plate.

I claim:

1. An armor plate installer consisting of 12 two beams, the lower ends adapted to be adjustably fastened to the side of the hull of the ship by means of angles, the tops of the beams held in spaced relation to each other by means of adjustable rods, the 12 beams slanting in an upward direction away from the hull and away from each other, the tops of the beams adapted to be connected to the top of the hull by suitable means.

2. An armor plate installer consisting of 13

two beams, the lower ends adapted to be adjustably fastened to the side of the hull of the ship by means of angles and also to the top of the hull by means of cables and 5 clamps, the tops of the beams held in spaced relation to each other by means of adjustable rods, the beams slanting in an upward direction away from the hull and away from each other, the tops of the beams 10 adapted to be connected to the top of the hull by suitable means.

3. An armor plate installer consisting of

two beams, the lower ends adapted to be adjustably fastened to the side of the hull of the ship by means of angles and also 15 to the top of the hull by means of cables and clamps, the tops of the beams held in spaced relation to each other by means of adjustable rods, the beams slanting in an upward direction away from the hull, the tops of the 20 beams adapted to be connected to the top of the hull by suitable means.

LESLIE SALTER.
